**MEANS FOR INSURING QUIET OPERATION OF
WASTE COLLECTING VACUUM SYSTEM**

Frank E. Rowe, Jr., Hingham, Mass., assignor to Abington Textile Machinery Works, North Abington, Mass., a trust of Massachusetts

Application July 21, 1953, Serial No. 369,438

7 Claims. (Cl. 230—115)

This invention relates to the provision of means for eliminating objectionable noise that has heretofore been an incident of operation of vacuum systems used in the removal of industrial waste.

While the vacuum system that will hereinafter be explained and with which the invention is used has had its principal use in connection with the cleaning of textile machinery and the like, it will be understood that the invention is applicable to any system in which a sufficiently high vacuum is produced by a centrifugal vacuum or suction pump.

In those vacuum or suction cleaning systems of such capacity that adequate negative pressure can be produced simultaneously at many cleaning points, it is obvious that a large volume of air must be continuously removed. By the removal of air from the pipes of the system, the pressure drops at the cleaning nozzles causing an inrush of air into the nozzles which carries with it the waste that is to be removed. To produce this result, the high speed centrifugal suction pump has come into general use. This machine is capable of moving a sufficient volume of air to reduce the pressure in the various lines to the degree necessary to provide an adequate velocity of air into the cleaning nozzles at the various cleaning positions to do a satisfactory waste removing operation.

In the typical textile factory having various types of machinery to be cleaned, such as carding engines, looms, and spinning frames, the vacuum cleaning is not necessarily performed at the same time at each type of machine. Accordingly, the suction lines have valves installed at appropriate points which may be opened whenever cleaning is to be undertaken at particular places. The centrifugal pump, however, which supplies the necessary suction for all of the cleaning positions will ordinarily be operated continuously with the cleaning load varying in accord with the particular cleaning requirements.

If cleaning is going on simultaneously at all cleaning positions, a greater volume of air will flow through the pump in a unit of time and the buildup to maximum negative pressure will occur more slowly than would be the case if only part of the cleaning mechanism were in use.

It will be understood that air is of an elastic nature and under the influence of the continuously operating centrifugal pump, the air in the suction lines becomes more and more attenuated as the negative pressure increases. Likewise, the pressure differential between the suction and discharge sides of the pump gradually increases, the discharge side remaining at a figure slightly above atmospheric. In due course when this pressure differential becomes great enough, the atmospheric pressure on the discharge side is large enough to force air backward through the centrifugal pump to the suction side of the pump where the pressure is so much less. The movement of air in a backward direction through the centrifugal pump which is rotating at high speed, produces a high pitched squeal or shriek which is very objection-

2

able to the ear. This squeal is carried in full volume to the outlet end of the discharge pipe, which end is customarily located outside of the building. This unpleasant sound is of such frequency and amplitude that it can be heard for a long distance.

The squeal continues so long as air from the discharge side of the pump is moving backward past the blades of the pump into the suction system. This reverse movement of air will continue until the pressure differential between the suction and discharge sides of the pump is reduced to a certain figure, at which time the pump blades again become effective to move air to the discharge side, reducing the pressure on the suction side in a matter of seconds to a point where the differential is sufficient to again cause reverse air flow with the attendant squeal.

It is apparent therefore that so long as the pump is able to increase the negative pressure to a degree sufficient to produce the required pressure differential, a series of objectionable squeals or shrieks will be produced. The frequency of the squeals will increase as the amount of air entering the suction line is decreased and the pitch of the squeals will vary as the absolute volume of the suction lines may be changed through the actuation of the various shut-off valves.

Accordingly, it is an object of this invention to provide means which will act in combination with a suction system of the type described utilizing a centrifugal pump which will effectively stop the squealing which up to the present has been considered a necessary evil incident to the use of this type of equipment.

A further object of the invention is to provide a specially designed unit which may be attached directly to the discharge side of the suction pump and in series with the remainder of the outlet piping which will be effective at once to prevent the disturbing squealing noise.

These and other objects of the invention will become more apparent as the description proceeds with the aid of the accompanying drawings in which

Fig. 1 is a schematic showing of a typical suction system for waste collecting in a textile mill.

Fig. 2 is an enlarged vertical cross-section of the antisurge valve which is installed in the discharge side of the pump.

Fig. 3 is a section on the line 3—3 of Fig. 2.

In Fig. 1 there is shown a centrifugal vacuum pump 2 driven by a motor 3 and having a discharge pipe 4 passing to the atmosphere through the wall of the building 6. The discharge pipe 4 includes a rubber vibration sleeve 8 and an antisurge valve 10 which will be described more particularly hereinafter.

The suction side of the pump includes in the present disclosure the following elements: A gate valve 14, rubber vibration sleeve 16, piping 18 leading to two waste receivers 20 and 22 connected in parallel, which waste receivers have at their upper ends shut-off valves 24 and 26. It is customary to use only one waste receiver at a time, thus permitting the other to be cleaned. A pipe 28 leads from T 27 to a shut-off valve 30 beyond which are individual suction pipes 32 and 34 utilized in removing waste from the spinning frames 36 or such other equipment that is to be cleaned.

The pipe 38 leading from T 27 has therein shut-off valve 40, beyond which are individual suction pipes 42 and 44 leading downwardly through valves 46 and 48 to the suction nozzles 50 and 52 utilized in cleaning the cylinders 54 and 56 of the carding engines or other equipment.

The various elements of the system just described are conventional except for the antisurge valve 10, the introduction of which has brought about the result of

quiet operation which has heretofore been sought, but never attained with this type of equipment.

The antisurge valve which is shown in detail in Figs. 2 and 3 will now be described. The valve comprises a cylindrical housing of varying dimensions. It has a lower end 58 adapted to make connection with the exhaust side of pump 2. This end expands upwardly in conical formation as at 60 to connect with an enlarged cylindrical section 62, the two parts being secured by a plurality of bolts 64 which pass through outwardly turned flanges 66 and 68. The enlarged cylindrical section 62 is necessary to provide for a screen 70 that will have sufficient free space therethrough to be at least equal to the area of the connection with the exhaust side of the pump. This screening is secured between the flanges 66 and 68 by the bolts 64.

Within the cylindrical section 62 is a conically shaped section 72 having at its bottom end a flange 74 which likewise is secured between the flanges 66 and 68 by the bolts 64. The upper end of the conical section 72 terminates in a cylindrical section 76 on which is mounted a pressure operated one-way valve unit. This valve consists of a cylindrical sleeve 78 with an inturned flange 79 which is placed on the upper end of the cylindrical portion 76. At one side is an extension for supporting a hinge 80 to which is pivoted a valve 82 which valve when in horizontal position as shown in Figs. 2 and 3 is closed and will prevent the flow of air downwardly in the reverse direction through pipe 4. When the pressure on the under side of valve 82 exceeds that above, the valve will then swing to open position as shown in the dotted lines in Fig. 2, thus permitting air to flow upwardly through the unit as it is discharged from pump 2.

The upper end of cylindrical section 62 has an outwardly turned flange 84 to which is secured the flange 86 of the conical section 88 by the bolts 90. The upper end of section 88 is shaped as at 92 for connection to the pipe 4.

The weight of valve 82 is relatively small and because of its appreciable area only a small pressure differential is required to open it to permit air to flow from the exhaust side of the pump at 58 through valve 82 to the pipe 4 leading to the outside atmosphere. That is to say, the introduction of the valve 82 has very little effect on the normal operating efficiency of the system in that the additional back pressure caused by valve 82 is, for practical purposes, negligible.

The mode of operation of the invention is as follows: Let us assume that all parts of the mill, for example, the spinning room, the weave room, the card room and the picker room, are to be cleaned at the same time. In such case, a maximum amount of air will be drawn by the vacuum pump 2 and expelled to the atmosphere through pipe 4. Valves 14, 24, 30 and 40 will be opened, thus creating a negative pressure in the piping which will permit the cleaning of the various machines through the use of the subsidiary connecting pipes 32, 34, 42 and 44 and other piping not shown which would lead to the weave room and picker room. The waste picked up from the various machines is carried through pipes 28 and 38 to be deposited in one or both of the receivers 20 and 22 in which there are filters so that the air leaving receivers and passing through pipe 18 to the suction pump 2 will be substantially clean. As the pump 2 continues in operation, the negative pressure in the pipe 18 increases to a point where the differential in pressure between that of pipe 18 and that on the exhaust side of the pump is such that in the absence of the antisurge valve 10, atmospheric air in pipe 4 will reverse its direction, flow back into pump 2 and thence back into line 18 with the attendant objectionable squeal until such time as the pressure differential is reduced so that the pump again becomes effective to cause air flow in the normal direction.

The introduction of the antisurge valve 10, however,

at a position immediately above the discharge side of the pump has eliminated this troublesome noise. The reason for this is that while the pressure of the air within the very short section of pipe 58 and the lower part of the surge valve unit below the valve 82 is of such small volume that even though it may start backwardly through the pump when the pressure differential becomes great enough, the pressure falls below atmospheric rapidly because of the small air volume, and hence the required pressure differential necessary to initiate and continue this backward flow is immediately eliminated. That is to say, the reverse flow stops almost immediately after starting and therefore no sound is caused. The amount of air that can flow backward is limited by the operation of valve 82 and the resultant immediate pressure drop. As soon as any backward flow in pipe 58 commences, the air in pipe 4 influenced by the pressure drop in 58 likewise moves in the reverse direction. This in turn instantly closes valve 82 or maintains it closed if it was in that position, thus limiting the air that can flow backward through the pump 2 to a very small part of that which was in the antisurge valve unit below valve 82. In other words, the movement of a very small amount of air from the antisurge valve unit in the reverse direction, which amount is insufficient to cause the commencement of the squeal, will reduce the pressure differential below that necessary to cause reverse movement. Thus, regardless of the attenuation of the air in the suction line, no appreciable reverse flow can occur and squealing is eliminated. The pump can therefore operate continuously at full efficiency without objection by persons in the neighborhood.

From the foregoing explanation, it can be seen that the improvement resides in the combination of elements which includes therein a pressure operated one-way valve that is located so close to the exhaust side of the vacuum pump that there will be an insufficient volume of air between the valve and the pump to cause any appreciable reverse flow to the pump after the pressure differential has become great enough to cause the initiation of such flow.

It should further be pointed out that the number of squeals occurring per minute under the prior practice varied with the total volume of piping in use on the suction side of the pump. The greater the volume of the piping, the lower the number of squeals per minute. The less the volume, the higher the number of squeals per minute. This is believed to be due to the fact that with a large volume of piping in use, the air flow in reverse direction through the pump would occur for a longer period as a greater amount of air continuously under atmospheric pressure would have to flow backward into pipe 18 to reduce the pressure differential enough to stop reverse flow than would be the case if the volume of the piping in use were less. In other words, if for example the valve 30 were closed, cutting off all the suction piping from the spinning room, then the frequency of the squeals would immediately increase.

Now, however, by the introduction of the antisurge valve 10, squealing is entirely eliminated regardless of the extent of the suction system in use at any time.

While the explanation of the improved results obtained as stated above is believed to be correct, it should be understood that no reliance is placed on this theory as other conditions unknown at this moment may be effective within the piping. The invention hereinafter claimed resides in the combination of elements which have been found effective to produce this beneficial result of silencing vacuum cleaning systems of the type described in a manner heretofore unknown.

It is my intention to cover all changes and modifications of the example of the invention herein chosen for purposes of the disclosure which do not constitute departures from the spirit and scope of the invention.

I claim:

1. In a vacuum cleaning system comprising a centrifugal vacuum pump, a suction line and an exhaust line, a one way valve unit in said exhaust line located close to said pump, said valve unit comprising an enlarged casing having a cross-sectional area which is larger than the cross-sectional area of the portion of the exhaust line to which said unit is connected, means forming a passage extending within said casing, the end of which has an opening forming a valve seat, said passage means communicating with the exhaust line and being spaced from the wall of the center section of the casing, and a pressure operated valve movable upwardly away from and downwardly toward said seat, said valve being moved downwardly to said closed position in response to initiation of backward flow, the volume of the exhaust line between said valve and pump when said valve is closed being insufficient to provide a back flow of gas through said pump which will cause undesirable shriek when the pressure differential between the suction and pressure sides of said pump causes backward flow to occur.

2. A system according to claim 1 wherein said passage means is of varying cross-sectional size in the direction of gas flow.

3. A system according to claim 2 wherein said passage means is conical in shape.

4. A system according to claim 1 wherein said pressure operated valve when full open having substantially the capacity of said exhaust line.

5. A vacuum cleaning system comprising a centrifugal vacuum pump, a suction line and an exhaust line, said exhaust line including therein a one-way valve unit located close to said pump, said valve unit comprising an enlarged casing, two end sections, one of diminishing cross-sectional area in the direction of gas flow and the other of increasing cross-sectional area in the direction of gas flow, and a central enlarged section connecting

said end sections, said enlarged center section and the wider ends of said end sections being larger in cross-sectional area than the portion of the exhaust line to which said unit is connected, means forming a passage within said casing, said passage means being of varying cross-sectional size in the direction of gas flow and the end of which has an opening forming a valve seat, said passage means communicating with the exhaust line and being spaced from the wall of the center section, and a pressure operated valve cooperating with said valve seat permitting substantial flow of air away from said pump only.

15 6. A pneumatic system comprising a centrifugal pump, an exhaust line and a valve unit in the exhaust line, said unit comprising a first cylindrical end of substantially the size of the exhaust pipe to which it is to be connected, said end connected to a conical section connecting in turn with an enlarged cylindrical center section, a second conical section leading from said center section to a second cylindrical end which is substantially the same size as said first end, a conical baffle with a central opening located within said cylindrical section and connected thereto, a pressure operated valve mounted in said opening with said valve movable from closed to open position in the direction of said second end.

20 7. A system as set forth in claim 6, said valve being pivoted on said baffle and positioned to swing in a vertical arc.
